CUTTING KNIFE SLOT CLOSING PLATE

Frederick W. Seybold, Westfield, N. J., assignor
to E. P. Lawson Company, Inc., New York, N. Y.,
a corporation of New York.

Application June 4, 1947, Serial No. 752,541

6 Claims. (Cl. 164—54)

1

My present invention is primarily an improvement over the invention shown in my application Serial No. 673,289 filed May 31, 1946, and relates particularly to the construction of a slot closing plate for a cutting knife, which plate is so arranged that it will maintain the slot closed irrespective of the amount of wear or other adjustment of the knife itself during use thereof.

In the operation of cutting knives of the so-called guillotine type as exemplified by my above-mentioned application, the knife, which cuts a stack of sheets comes down not only with a downward movement but also with a swinging lateral movement, usually moving toward the left in its downward swing.

For this reason, the knife bar and blade rides in a pair of slots on opposite sides of the work table which guide the knife blade and, at the same time, permit the knife blade and bar to swing laterally during the downward stroke.

The lateral swing of the knife bar during the downward stroke has the effect of forcing the paper stack, as a whole, against the left-hand gauge, and hence against the slot traversed by the knife blade.

Of course, the paper stack is placed against the left-hand gauge initially, but the pressure of the knife blade as it swings laterally tends to drive the paper stack very tightly against the left-hand gauge. Trimmings, or small narrow piles such as small labels, tend, therefore, to be driven into the slot on the left side in which the knife bar rides.

Where a narrow cut is taken, the operation of the knife bar in this manner tends to sweep or pull all of the narrow strips severed into the knife slot. For this reason, it has become desirable to close the slot in such manner that the closure may automatically be opened by the descent of the knife blade but, nevertheless, so that the closure member also automatically closes up the slot at every position of the knife blade.

Thus, attempts have been made to utilize the rotatable closure plates which are swung out of the way on the descent of the knife blade or slideable closure plates which are pushed down on the descent of the knife blade and rise up once more when the knife blade rises.

It is possible to make such closure plates either swinging or sliding so that they will operate properly for one adjustment of the knife bar and for one exact width of blade. However, as the knife continues in use, the blade is continuously sharpened and resharpened and, therefore, becomes shorter.

2

As a matter of fact, after it has been shortened by sharpening, it may be adjusted to an entirely new position on the knife bar, in most cases, where it is again relatively wide or projects relatively far below the knife bar.

A primary object of my present invention is to provide therefore, an adjustable slot closing plate which may be automatically adjusted for any adjustment of the knife bar and for any relative width of knife blade so that the slot will always be completely closed. This is extremely important since, even a relatively very narrow aperture at the upper end of the slot, adjacent the knife blade as the knife blade wears will permit one or two or more strips to be forced into the slot and these strips will damage the top of the paper pile in process of being cut.

A further object of my invention is the provision of simplified operating means for the slot closure plate so arranged that it will automatically follow the operation of the knife bar in both directions.

Another object of my invention is the provision of simplified adjusting elements for my novel slot closing plate.

The foregoing and many other objects of my invention will become apparent in the following description and drawings in which:

Figure 1 is a partial view in perspective of my novel slot closing plate in conjunction with a fragmentary view of the knife bar and knife with which it is to cooperate.

Figure 2 is a cross-sectional view through my novel slot closing plate and a portion of the knife frame, said section being taken on line 2—2 of Figure 1.

Figure 3 is a side view partly in cross-section of my novel slot closing plate.

Figure 4 is a top view of my novel slot closing plate taken from line 4—4 of Figure 3.

Figure 5 is a cross-sectional view taken on line 5—5 of Figure 3.

Figure 6 is a cross-sectional view taken on line 6—6 of Figure 3.

Figure 7 is a view corresponding to that of Figure 3 showing, however, a slightly modified form of slot closing plate.

Figure 8 is a cross-sectional view taken on line 8—8 of Figure 7.

Referring now to the figures, the knife bar 10 carrying the knife blade 11 is actuated up and down in any suitable manner as shown in my prior application Serial No. 673,289 in slots 16 in the main frame 14, the said slots being defined by 55 the side guides 12 and 13 (Figure 2). Guide 13 may

be a fixed guide in each of the slots and guide 12 may be adjustable by the wedge 19 which may be moved in and out by the adjusting screw 20 also as described in my aforesaid prior application. The left side guide is formed by portion 14a of frame 14 back of slot 16, the slot closing plate 25 and the additional side gauge member 21 forward of the slot. The paper to be cut rests of course on table 22, the slot closing plate is guided and positioned for vertical sliding movement by guide 23 in front gauge 21 which guide cooperates with the vertical member 27 secured to the slot closing plate 25. The rear end of the slot closing plate is guided by guide 26 in slot 16 which guide however starts below the level of table 22 and does not interfere with the movement of the knife.

As previously pointed out, the knife bar 10 and its associated blade 11 not only have a downward movement but also have a movement toward the left so that the knife blade acts as a laterally swinging guillotine. This movement toward the left tends to drive scraps of paper and especially narrow strips when they are severed by the knife bar into the left-hand slot 16.

For this reason, a slot closing plate is required. Various types of slot closing plates have been used. But the difficulty has arisen that as the knife blade 11 is continuously sharpened, it varies its relative width with respect to the knife bar 10 so that at first a small gap appears between the slot closing plate and the knife blade and as the blade is shortened by further continuous sharpening, the gap widens sufficiently to permit relatively large quantities of paper to be cumulatively jammed into the slot 16.

For this purpose and in order to obviate this difficulty, my invention contemplates an adjustable slot closing plate 25 having a main body which slides up and down in the slot and which, with the additional elements below described, completely fills the slot at all times so that paper particles and other material can not be jammed into the slot despite the lateral movement of the knife bar 10 and the blade 11.

The main body of the slot closing plate 25 has a vertical member 27 secured thereto in any suitable manner as by the rivets 28, the said vertical element 27 extending up to just above the top surface of the knife bar 10.

The vertical member 27 thus comprises a rigid link extending above the main body of the slot closing plate 25 and carries at its upper end a pin 29 on which is mounted the roller 30 which roller 30 extends above the top surface 31 of the knife bar 10.

As the knife bar 10 and blade 11 descends, they carry the slot closing plate 25 down with them; and as they rise, the upper surface 31 of the knife bar 10 pulls up the roller 30, pulling up the slot closing plate 25.

The roller 30 rolls on the top surface 31 of the knife bar 10 so that the slot closing plate 25 may have no lateral movement while the knife bar 10 moves laterally as well as downwardly.

The slot closing plate has a rearward extension 35 which is vertically adjustable. The upper end 36 of the rearward extension 35 is adapted to register with the lower surface of the knife blade 11, while the upper surfaces 37 and 38 of the main body 26 of the slot closing plate are adapted to register with the lower surface of the knife bar 10.

The body 25 of the slot closing plate is vertically slotted and undercut at 40 to provide

a recess in which the vertical lug 41 of the adjustable member 35 may slide. The upper surface 38 of the main body 26 of the slot closing plate is provided with an opening 42 having the counterbore 43 to receive the bolt 44 having the head 45, the head 45 being recessed in the counterbore 43.

The upper surface 50 of the lug 41 of the adjustable member 35 is provided with the vertically tapped opening 51 in which the lower end of the bolt 44 is threaded. When the bolt 44 is rotated by means of a socket wrench engaged in socket 53 thereof, the vertically adjustable member 35 and its lug 41 are raised or lowered in accordance with the sense of rotation.

The adjustment is automatically locked in position by the spring biased lug 55, the point of which is pushed against the grooves 56 in the head 45 of the bolt by the compression spring 57. The locking lug 55 and spring 57 are mounted in the lateral recess 60 which communicates with the counterbore 43 and thereby permits the locking lug 55 to be effective.

Thus, as the knife blade 11 is continuously sharpened and reduced in width so that it projects to a lesser degree from the lower end of the knife bar 10, the rotation of the bolt 44 raises the adjustable element 35 so that the upper end 36 thereof is closely in engagement with the lower end of the knife blade 11. Every time the blade 11 is sharpened and thus reduced in its vertical dimension, the adjustment may be made to insure closing of the knife slot.

When the blade 11 is finally replaced by a longer blade, then the adjustment is made to lower the adjustable member 35 so that the upper end 36 thereof is in close engagement with the lower end of the blade.

The upper surface of the slot closing plate is made accessible in any suitable manner.

Thus the pin 29 for roller 30 is mounted in vertical bracket 70 having the horizontal flange 71 resting on lug 72 secured to the top of extension 21. Pin 75 keyed to flange 71 passes through an opening in lug 72 and furnishes a rotatable pivot for bracket 70 to rotate the roller out of engagement with top 31 of knife bar 10. Clamping nut 77 is used to lock pin 75 and hence roller 30 in position. Thus, when it is necessary to adjust the blade or the slot closing plate, the nut 77 is loosened and roller 30 is rotated to the dotted line position of Figure 1. The slot closing plate may then be dropped and the top is accessible for adjustment. When adjustment is completed, the roller 30 is then rotated back over the top 31 of knife bar 10 to connect plate 25 with the knife bar once more.

By this means, therefore, a simplified adjustable slot closing plate is provided which will be universally adaptable over the entire range of use of the knife and which will automatically be adaptable to the closing of the slot irrespective of the vertical dimension of the blade.

In Figures 7 and 8 I have shown a slight modification in which slot closing plate 125 having extension 127 attached thereto by rivets 128 has a vertically adjustable extension 135 with a lug 141 riding in recess 140 of plate 125. Compression spring 80 in recess 140 bears between the bottom of lug 141 and the bottom ledge 81 of the recess 140. Bolt 144 in tapped opening 142 rides up and down when its head 145 in counterbore 143 is rotated. The bottom end of bolt 144 bears against the top 83 of lug 141 to push it down and hence push down adjustable extension 135 against the

compression of spring 80; when bolt 144 is raised, spring 80 drives extension 135 up. Thus, extension 135 is lowered by turning bolt 144 in one direction and is raised by spring 80 when bolt 144 is turned in the opposite direction.

In the foregoing, I have described my invention solely in connection with specific preferred embodiments thereof. Since many variations and modifications of my invention will now be obvious to those skilled in the art, I prefer to be bound not by the specific disclosure herein contained but only by the appended claims.

I claim:

1. In a cutting machine having a frame, a work table and a vertically reciprocating knife bar, said knife bar having also a lateral component of motion and moving in vertical slots in said frame, said knife bar carrying a blade extending below said knife bar, the degree to which said blade extends below the knife bar varying during the use of the machine; a slot closing plate mounted to close the slot toward which the knife bar moves laterally as it descends and closing the slot from the knife bar and blade to the work table; said plate moving up and down in said slot as the knife bar reciprocates vertically and maintaining the slot closed in every position of the knife bar; a portion of the upper end of the plate engaging the lower end of the knife bar; and another portion of the upper end of the plate engaging the blade; the blade engaging portion being vertically adjustable in accordance with the degree to which the blade extends beneath the knife bar.

2. In a cutting machine having a frame, a work table and a vertically reciprocating knife bar, said knife bar having also a lateral component of motion and moving in vertical slots in said frame, said knife bar carrying a blade extending below said knife bar, the degree to which said blade extends below the knife bar varying during the use of the machine; a slot closing plate mounted to close the slot toward which the knife bar moves laterally as it descends and closing the slot from the knife bar and blade to the work table; said plate moving up and down in said slot as the knife bar reciprocates vertically and maintaining the slot closed in every position of the knife bar; a portion of the upper end of the plate engaging the lower end of the knife bar; and another portion of the upper end of the plate engaging the blade; the blade engaging portion being slidably mounted with respect to the knife bar engaging portion and being vertically adjustable with respect thereto.

3. In a cutting machine having a frame, a work table and a vertically reciprocating knife bar, said knife bar having also a lateral component of motion and moving in vertical slots in said frame, said knife bar carrying a blade extending below said knife bar, the degree to which said blade extends below the knife bar varying during the use of the machine; a slot closing plate mounted to close the slot toward which the knife bar moves laterally as it descends and closing the slot from the knife bar and blade to the work table; said plate moving up and down in said slot as the knife bar reciprocates vertically and maintaining the slot closed in every position of the knife bar; a portion of the upper end of the plate engaging the lower end of the knife bar; and another portion of the upper end of the plate engaging the blade, the blade engaging portion being slidably mounted with respect to the knife bar engaging portion and being vertically

adjustable with respect thereto; means for adjusting said blade engaging portion vertically with respect to the knife bar engaging portion in accordance with the degree to which the blade extends beneath the knife.

4. In a cutting machine having a frame, a work table and a vertically reciprocating knife bar, said knife bar having also a lateral component of motion and moving in vertical slots in said frame, said knife bar carrying a blade extending below said knife bar, the degree to which said blade extends below the knife bar varying during the use of the machine; a slot closing plate mounted to close the slot toward which the knife bar moves laterally as it descends and closing the slot from the knife bar and blade to the work table; said plate moving up and down in said slot as the knife bar reciprocates vertically and maintaining the slot closed in every position of the knife bar; a portion of the upper end of the plate engaging the lower end of the knife bar; and another portion of the upper end of the plate engaging the blade, the blade engaging portion being slidably mounted with respect to the knife bar engaging portion and being vertically adjustable with respect thereto; means for adjusting said blade engaging portion vertically with respect to the knife bar engaging portion in accordance with the degree to which the blade extends beneath the knife, said means comprising a screw rotatably mounted in said knife bar engaging portion of the plate and in threaded engagement with the blade engaging portion of the plate.

5. In a cutting machine having a frame, a work table and a vertically reciprocating knife bar, said knife bar having also a lateral component of motion and moving in vertical slots in said frame, said knife bar carrying a blade extending below said knife bar, the degree to which said blade extends below the knife bar varying during the use of the machine; a slot closing plate mounted to close the slot toward which the knife bar moves laterally as it descends and closing the slot from the knife bar and blade to the work table; said plate moving up and down in said slot as the knife bar reciprocates vertically and maintaining the slot closed in every position of the knife bar; a portion of the upper end of the plate engaging the lower end of the knife bar; and another portion of the upper end of the plate engaging the blade, the blade engaging portion being slidably mounted with respect to the knife bar engaging portion and being vertically adjustable with respect thereto; means for adjusting said blade engaging portion vertically with respect to the knife bar engaging portion in accordance with the degree to which the blade extends beneath the knife, said means comprising a screw rotatably mounted in said knife bar engaging portion of the plate and in threaded engagement with the blade engaging portion of the plate and means for locking the screw in adjusted position.

6. In a cutting machine having a frame, a work table and a vertically reciprocating knife bar, said knife bar having also a lateral component of motion and moving in vertical slots in said frame, said knife bar carrying a blade extending below said knife bar, the degree to which said blade extends below the knife bar varying during the use of the machine; a slot closing plate mounted to close the slot toward which the knife bar moves laterally as it descends and closing the slot from the knife bar and blade to

the work table; said plate moving up and down in said slot as the knife bar reciprocates vertically and maintaining the slot closed in every position of the knife bar; a portion of the upper end of the plate engaging the lower end of the knife bar; and another portion of the upper end of the plate engaging the blade; the blade engaging portion being vertically adjustable in accordance with the degree to which the blade

extends beneath the knife bar and an additional extension from said knife bar engaging portion of the plate connected to another portion of the knife bar for vertical reciprocation of the plate by the knife bar.
